GUN WITH BARREL-RECOIL OF UNIFORM LENGTH.

1,010,908.

Specification of Letters Patent.

Patented Dec. 5, 1911.

Application filed April 4, 1911. Serial No. 618,786.

To all whom it may concern:

Be it known that I, WALTER HEILEMANN, a subject of the Emperor of Germany, and a resident of Essen-on-the-Ruhr, Germany, ⁵ have invented certain new and useful Improvements in Guns With Barrel-Recoil of Uniform Length, of which the following is a specification.

In recoil guns such as curved fire guns, ¹⁰ which may be fired at great elevations and which shall have in the first place a normal firing height and in the next place great stability when fired at reduced elevation, it is well known to construct the recoil ¹⁵ brake in such a manner that the gun barrel has a long recoil with small elevations and a short recoil with great elevations. Such a construction (variable recoil) is comprised in a complicated and delicate construction. To avoid the drawbacks attending ²⁰ variable recoil, the horizontal trunnions have been displaced into the immediate vicinity of the breech end of the gun barrel when the latter is in the firing position to ²⁵ the end that the gun barrel may have a long recoil not alone with low elevations but with high elevations as well, without the firing height exceeding the normal amount. But as the backward displacement of the ³⁰ horizontal trunnions produces a considerable overbalancing to the front end of the revolute system, this type of gun with a uniformly long recoil has been provided with a compensating device (a spring or the like) ³⁵ constructed in the form of a power storing device. The sensitiveness of this type of compensating device is not to be denied. Efforts have heretofore been made to eliminate accumulating compensating devices in ⁴⁰ guns with uniformly long recoil, and this has been sought to be accomplished among other ways, in guns provided with trunnions in the immediate vicinity of the breech end of the barrel, by prolonging the slide ⁴⁵ track carrier beyond the breech end of the gun barrel to an extent corresponding to the length of recoil, and arranging a counterbalance on the rear end of the slide track carrier. But a counterbalance such as this ⁵⁰ (on the slide track carrier) constitutes a dead load in addition to which guns of this construction have a cumbersome appearance.

The purpose of this invention is to provide ⁵⁵ a recoil gun to be fired at great eleva-

tions in which the objections referred to in recoil guns of known design, are avoided, notwithstanding that the normal firing height is not exceeded and a sufficient stability is preserved when firing. ⁶⁰

A curved fire recoil gun is shown in the drawing as a constructional example of this invention.

Figure 1 is a side view of the parts under consideration of such a gun; and Fig. 2 is ⁶⁵ a plan view of Fig. 1.

The gun constituting the subject matter of the invention has a barrel recoil of uniform length. The gun barrel A is guided in the usual manner on the slide track carrier B which is journaled by means of the horizontal trunnions ⁷⁰ b^1 in the gun carriage C, and can be rotated about the axis of the horizontal trunnions by means of an elevating mechanism not shown in the drawing. The slide track carrier contains a brake whose cylinder is designated by E and a recuperator F. The brake cylinder is connected to the gun barrel by means of a horn a^2 . This horn and the end of the brake ⁷⁵ cylinder attached thereto are disposed at a considerable distance forward of the rear surface of the breech of the gun barrel.

The horizontal trunnions ⁸⁰ b^1 are backwardly displaced. By this term is intended to be designated such an arrangement of the trunnions that they lie behind the center of gravity of an ideal system formed by the gun barrel, the brake together with the recuperator and the slide track carrier, a system distinguished from the corresponding system shown in the drawing in this respect, that in the first mentioned system the slide track carrier terminates in the vicinity of the front face of the breech end of the gun ⁸⁵ barrel, when the latter is in firing position and that the breech end possesses normal dimensions. The backward displacement of the trunnions is not so great as to seat them in the immediate vicinity of the breech end ⁹⁰ of the gun barrel but, in the well known manner, only so far back as will permit the part of the gun barrel lying behind them to counterbalance a considerable portion of the weight of the parts lying in front of it, of the system oscillating about the horizontal trunnions. The system revoluble upon the trunnions ⁹⁵ b^1 would nevertheless possess a considerable overbalance forward, in case the slide track carrier should terminate in ¹⁰⁰ 105 110

the vicinity of the front face of the breech end when the barrel is in firing position, and the breech end have the normal dimensions. Now this forward weight is compensated in 5 part by the breech end of the barrel enlarged beyond the normal dimensions (at a^1 , Fig. 1) and in part completely or approximately compensated by the fact that the slide track carrier B is extended beyond the 10 breech end of the gun when the latter is in the firing position to an extent less than the length of the recoil. The enlargement of the breech (somewhat exaggerated in the drawing) is well known, as well as the extension of the slide track carrier to the extent described.

In consequence of the described position of the horizontal trunnions, the enlargement of the breech end of the gun barrel, and the 20 extension of the slide track carrier beyond the breech end, as is plain without further description, a uniformly long recoil can be employed with all elevations (compare the positions I and II of the gun barrel, etc., 25 shown in dotted and dash lines in Fig. 1) without the firing height exceeding the normal amount. But by means of the long recoil a sufficient stability is attained in firing at all elevations. Besides this the gun described in addition to having a simple structure is of pleasing appearance.

A 10.5 centimeter howitzer constructed in accordance with this invention, would have, with a firing height h of about 1 m., a length 35 of recoil r likewise about 1 m. This length of recoil is somewhat less than that longest customary recoil of a howitzer with variable barrel recoil, and than the usual recoil of a howitzer, whose trunnions lie immediately 40 at the breech end of the gun barrel, and having a similar firing height, etc. Nevertheless, a howitzer of the present type possesses about the same stability when firing as the type of howitzer just referred to since, in 45 consequence of the enlargement of the breech end of the gun barrel, the mass of the recoiling system is increased, and the center of gravity of the recoiling system is brought nearer to the axis of the bore of the gun 50 barrel, circumstances which, as well known favor the stability of a gun.

It should also be mentioned that, owing to the fact, that the part of the brake connected to the gun barrel (the brake cylinder E) terminates in the usual manner considerably forward of the rear face of the

breech of the gun barrel a greater elevation, under otherwise equal conditions, can be given to the gun barrel with the usual arrangement of the brake cylinder in which 60 this latter terminates under the rear face of the breech and of the gun barrel, or even extends to the rear of said surface. The drawing (compare position II of the gun barrel and brake cylinder) clearly shows the 65 advantage of the above arrangement of the brake cylinder.

I claim:

1. In a recoil gun, a barrel having recoil of uniform length, a recoil brake the part of 70 which connected with said gun barrel terminating forwardly of the rear face of the breech end of the gun barrel, horizontal trunnions located in rear of the center of gravity of the members supported thereby but having in rear of them an enlarged portion of the gun barrel compensating a considerable portion of the forward weight supported by said trunnions, and a slide track carrier projecting beyond the rear end of 80 the gun breech, assisting in compensating the weight of the system swinging about the horizontal trunnions.

2. In a barrel recoil gun with recoil of uniform length, a slide track carrier upon 85 which the gun barrel is mounted, a brake having a part connected with the gun barrel, said part terminating in advance of the rear end of the breech of the gun barrel, horizontal trunnions on said slide track 90 carrier displaced toward the breech end of the gun barrel but leaving a substantial portion of the gun barrel in rear of said trunnions, said breech end of the gun barrel being enlarged beyond normal dimensions; 95 said slide track carrier being extended beyond the breech end of the gun barrel when the latter is in the firing position; said portion of the gun barrel in rear of the horizontal trunnions, with its enlargement, together with the extension of the slide track carrier, compensating the system swinging about the horizontal trunnions.

The foregoing specification signed at 105 Barmen, Germany, this 16th day of March, 1911.

WALTER HEILEMANN. [L. s.]

In presence of—

CHAS. J. WRIGHT,
ALFRED HENKEL.
